Primary Examiner — Robert M Spear*Assistant Examiner* — Darcey E Heflin(74) *Attorney, Agent, or Firm* — Reinhart Boerner Van Deuren S.C.(57) **CLAIM**

The ornamental design for a spout, as shown and described.

DESCRIPTION

FIG. 1 is a top perspective view of a spout;

FIG. 2 is a front view of the claimed design of FIG. 1;

FIG. 3 is a right side view of the claimed design of FIG. 1;

FIG. 4 is a rear view of the claimed design of FIG. 1;

FIG. 5 is a left side view of the claimed design of FIG. 1;

FIG. 6 is a top view of the claimed design of FIG. 1;

FIG. 7 is a bottom view of the claimed design of FIG. 1; and, FIG. 8 is a bottom perspective view of the claimed design of FIG. 1.

The ornamental design which is claimed is shown in solid lines in the drawings. In the drawings, the broken lines depict environmental subject matter only that forms no part of the claim.
